TOY REPEATER GUN

Erwin Benkoe, New Hyde Park, N.Y., assignor to Trans-
ogram Company, Inc., New York, N.Y., a corporation
of Pennsylvania

Filed Nov. 20, 1961, Ser. No. 67,587

Term of patent 14 years

(Cl. D34—15)

FIG. 2

FIGURE 1 is a front view of a toy repeater gun embodying my new design;

FIGURE 2 is a side elevational view thereof;

FIGURE 3 is a rear view thereof;

FIGURE 4 is a top plan view thereof; and

FIGURE 5 is a view looking up at the underside thereof.

I claim:

The ornamental design for a toy repeater gun, substantially as shown.
